UNITED STATES PATENT OFFICE.

JOHN WILLIAM SCHULZE, OF PROVIDENCE, RHODE ISLAND, ASSIGNOR TO ALFRED VESTER SONS, INC., OF PROVIDENCE, RHODE ISLAND, A CORPORATION OF RHODE ISLAND.

DESIGN FOR A PENDULET.

Application filed May 18, 1922. Serial No. 2,307. Term of patent 14 years.

To all whom it may concern:

Be it known that I, JOHN WILLIAM SCHULZE, a citizen of the United States, and residing at Providence, in the county of Providence and State of Rhode Island, have invented a new, original, and ornamental Design for a Pendulet, of which the following is a specification, reference being had to the accompanying drawing, forming part thereof.

Fig. 1 is a perspective view of a pendulet, showing my new design.

Fig. 2 is a side view of the same.

I claim:

The ornamental design for a pendulet, as shown.

JOHN WILLIAM SCHULZE.
